(57) **CLAIM**

The ornamental design for a food processing device, as
shown and described.

DESCRIPTION

FIG. 1 is a front-right perspective view of a food processing
device according to the claimed design;

FIG. 2 is a back-right perspective view thereof;

FIG. 3 is a front-left perspective view thereof;

FIG. 4 is a left perspective view thereof; and,

FIG. 5 is a front-right perspective view thereof showing the
food processing device mounted with an environmental
article.

Dash-dot-dash broken lines are environmental only and
form no part of the claimed design.

The portions of the article shown in evenly-dashed broken
line form no part of the claimed design.

Dash-dot-dot-dash broken lines adjacent un-shaded areas
represent bounds of the claimed design and form no part of
the claimed design themselves.
